UNITED STATES PATENT OFFICE.

FREDERICK W. RABEHL, OF ALEXANDRIA, MINNESOTA.

LITTER-CARRIER.

1,272,523.

Specification of Letters Patent. Patented July 16, 1918.

Application filed January 19, 1918. Serial No. 212,694.

To all whom it may concern:

Be it known that I, FREDERICK W. RABEHL, a citizen of the United States, residing at Alexandria, in the county of Douglas and State of Minnesota, have invented certain new and useful Improvements in Litter-Carriers, of which the following is a specification, reference being had to the accompanying drawings.

- 10 This invention relates to certain improvements in litter carriers and has relation more particularly to a device of this general character adapted to travel along an over-head track-way and it is an object of the invention to provide a device of this general character having novel and improved means whereby the contents of the carrier may be discharged therefrom in an automatic manner.
- 20 It is also an object of the invention to provide a device of this general character including a portable body provided with a swinging bottom together with means releasably engaged with said bottom for normally maintaining the same in closed position.

The invention consists in the details of construction and in the combination and arrangement of the several parts of my improved litter carrier whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be better understood, I will now proceed to describe the same with reference to the accompanying drawings, wherein:

Figure 1 is a view in elevation with portions broken away of a carrier constructed in accordance with an embodiment of my invention, the coacting track-way being shown in fragment;

Fig. 2 is a sectional view taken substantially on the line 2—2 of Fig. 1;

Fig. 3 is a view in end elevation of the device as herein embodied with the coacting track-way in section;

Fig. 4 is an enlarged sectional view taken substantially on the line 4—4 of Fig. 1; and

Fig. 5 is an enlarged fragmentary sectional view taken substantially on the line 5—5 of Fig. 3.

As disclosed in the accompanying drawings B denotes the body or receptacle included in my improved carrier and which has its top and bottom open. The lower 60 marginal portions of the body or receptacle B at the ends thereof converge downwardly as at 1 to substantially the transverse center of the body or receptacle B so that when the swinging doors 2 are in closed position, 65 a bottom for the body or receptacle is afforded which is substantially V-shaped in cross section. The doors 2 have their outer longitudinal marginal portions hingedly connected as at 3 with the lower marginal 70 portions of the side walls 4 of the body or receptacle B. The doors 2 are adapted to drop by gravity into open position so that the contents of the body or receptacle B may be discharged therefrom.

75

The inner longitudinal margin of each of the doors 2 at opposite ends thereof has secured to the outer face thereof the blocks 5. Each of the blocks 5 affords a substantially horizontal bottom face or surface 6 80 when the door 2 is in closed position.

Secured to the outer face of each of the ends 7 of the body or receptacle B, and at substantially the transverse center of said body or receptacle B, is an arm 8 extending 85 a predetermined distance above the top or open face of the body or receptacle B and terminating in the inwardly directed and substantially horizontal extension 9. The arms 8 and extensions 9 are in alinement 90 longitudinally of the body or receptacle B and secured to the opposite faces of the inwardly directed extensions 9 are the rigid members or straps 10 arranged in parallelism. Extending upwardly from each of the 95 inwardly directed extensions 9 and in swivel engagement therewith as indicated at 11 is a hanger 12 provided with a grooved roller or wheel 14 riding upon the track-way T and from which the body or receptacle B is 100 suspended.

Supported by the members or straps 10 at equi-distantly spaced points at opposite sides of the longitudinal center of the body or receptacle B and bridging the space between said members or straps 10 are the pins 15 or the like.

Pivotedly engaged to each of the pins 15 is the heel portion of a bell lever L. Each of the bell levers L includes a depending 110 arm 16 and the substantially horizontal and inwardly directed arm 17. The inner end

portions of the arms 17 of the bell levers L overlap and said overlapping portions are straddled by a fork 18 carried by the lower extremity of an arm 19 passing between the 5 rigid members or straps 10. The upper end portion of the arm 19 is provided with the grooved roller or wheel 20 adapted to contact with and ride along the lower portion of the track T. While the contact of the 10 wheel or roller 20 with the track T serves to limit the upward movement of the arm 19, said upward movement of the arm 19 is further limited by the fork 18 which is of a width in excess of the width of the space 15 between the members or straps 10.

At a predetermined point intermediate the fork 18 and the wheel or roller 20, the arm 19 has extending substantially at right angles therefrom and in a direction longitudinally of the members or straps 10, the 20 arm 21. The arm 21 is positioned above the members or straps 19 and terminates in the downwardly directed extension 22. The extension 22 extends between the members or 25 straps 10 and is pivotally connected with the pin 23 or the like bridging the space between the members or straps 10 at a point intermediate one of the pins 15 and the extension 9.

30 Pivots engaged with the lower or free end portions of the arms 18 of the levers L are the oppositely directed rods 24. Each of the rods 24 is provided at its outer end portion with the substantially U-shape yoke 35 having the outer or free end portions of the arms 26 thereof loosely directed through the upper end portion of the rock levers 27. The end portions of the arms 26 are provided with the enlargements or heads 28 40 constantly in contact with the adjacent end portions of the levers 27 for a purpose which will hereinafter be fully explained.

Secured to the outer face of each of the 45 ends 7 of the body or receptacle B, below the vertical center thereof and midway between the sides 4, is a plate 29 provided with transversely spaced pairs of outstanding ears 30.

Pivots engaged as at 31 between each 50 pair of ears 30 is one of the levers 27. The lower end of the lever 27 is provided with an inwardly directed arm 32 adapted to underlie and contact a bottom face or surface 6 of a block 5 to maintain a door 2 in closed 55 position. The arm 30 is provided at its free end portion with an outwardly and laterally curved bill or extension 33 to facilitate the passage of a door 2 by an arm 32 when the door is swung into closed position.

In vertical alignment with each plate 29 and positioned therebeneath is a second plate 34 also provided with transversely spaced pairs of outstanding ears 35. The 65 lower end portion of the lever 27 passes be-

tween a pair of ears 35 whereby said lower portion of the lever is held against lateral movement. Straddling the upper end portion of each of the levers 27 and pivotally engaged therewith as at 36 is a fork 37 carried by the outer end portion of a rod 38. The rod 38 is slidably engaged with an opening or recess 39 formed in the adjacent end 4 of the body or receptacle B. Interposed between the outer face of the end 4 and the fork 37 is an expansible member 40 herein disclosed as a conventional coiled spring encircling the rod 38. The expansible member 40 constantly urges the upper end portion of the coacting lever 27 outwardly so that the arm 32 at the lower end of said lever is maintained in proper position to engage a block 5 or is maintained in engagement therewith.

The tension of the several expansible 85 members 40 is sufficient to exert a pull upon the arm 16 of the bell lever L to maintain the arm 19 at the limit of its upward movement. As the device travels along the track-way T, the roller 20 will engage and ride over the cam C carried by and depending from the track-way T. As the arm 19 passes along the cam C, downward movement will be imparted to the arm 19 resulting in an inward movement of the rods 24 and an outward movement of the inwardly directed arms 32 carried by the levers 27. The movement of the rods 24 is sufficient to disengage the arms 32 of the levers 27 from the blocks 5 and whereby the bottoms 2 are permitted to drop or fall by gravity into open position and the contents of the body or receptacle B discharged. The bottoms 2 are returned manually to closed position. The device may be caused to travel along the 90 track-way in any desired manner, and as this forms no part of my present invention, a description and illustration thereof is believed to be unnecessary.

From the foregoing description, it is 110 thought to be obvious that a litter carrier constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to 115 the precise arrangement and formation of the several parts herein shown in carrying out my invention in practice except as hereinafter claimed.

I claim:

1. A device of the character described comprising in combination, an elevated track, a body, hangers carried by the body and riding upon the track-way, a hinged bottom for the body, levers pivotally en- 130

- gaged with the opposite end portions of the body and provided with arms underlying the bottom for holding the same in closed position, an inwardly directed arm operatively engaged with the opposite end portion of each of the levers, bell levers supported by the body, each of said bell levers including a depending arm and an inwardly directed arm, the inwardly directed arm of one bell lever overlapping the inwardly directed arm of the second lever, the depending arm of each of the bell levers being operatively engaged with the inner end of a rod, a substantially vertically disposed arm having its lower end engaged with the overlapping portions of the bell levers, the opposite end portions of the arm traveling along the under face of the track, an arm extending laterally from the first named arm and pivotally engaged with the body, a member carried by the track for imparting downward movement to the first named arm, and means coacting with the first named levers for constantly urging the same in one direction.
2. A device of the character described comprising in combination, an elevated track, a body, hangers carried by the body and riding upon the track-way, a hinged bottom for the body, levers pivotally engaged with the opposite end portions of the body and provided with arms underlying the bottom for holding the same in closed position, an inwardly directed arm operatively engaged with the opposite end portion of each of the levers, bell levers supported by the body, each of said bell levers including a depending arm and an inwardly directed arm, the inwardly directed arm of one bell lever overlapping the inwardly directed arm of the second lever, the depending arm of each of the bell levers being operatively engaged with the inner end of a rod, a substantially vertically disposed arm having its lower end engaged with the overlapping portions of the bell levers, the opposite end portions of the arm traveling along the under face of the track, an arm extending laterally from the first named arm and pivotally engaged with the body, a member carried by the track for imparting downward movement to the first named arm, and means coacting with the first named levers for constantly urging the same in one direction.
3. A device of the character described comprising in combination, an elevated track, a body, hangers carried by the body and riding upon the track-way, a hinged bottom for the body, levers pivotally engaged with the opposite end portions of the body and provided with arms underlying the bottom for holding the same in closed position, an inwardly directed arm operatively engaged with the inner end of a rod, a substantially vertically disposed arm having its lower end engaged with the overlapping portions of the bell levers, the opposite end portions of the arm traveling along the under face of the track, an arm extending laterally from the first named arm and pivotally engaged with the body, a member carried by the track for imparting downward movement to the first named arm, and means coacting with the first named levers for constantly urging the same in one direction and to normally maintain the first named arm at the limit of its upward movement.
4. A device of the character described comprising in combination, an elevated track, a body, hangers carried by the body and riding upon the track-way, a hinged bottom for the body, levers pivotally engaged with the opposite end portions of the body and provided with arms underlying the bottom for holding the same in closed position, an inwardly directed arm operatively engaged with the inner end of a rod, a substantially vertically disposed arm having its lower end engaged with the overlapping portions of the bell levers, the opposite end portions of the arm traveling along the under face of the track, an arm extending laterally from the first named arm and pivotally engaged with the body, a member carried by the track for imparting downward movement to the first named arm, and means coacting with the first named levers for constantly urging the same in one direction and to normally maintain the first named arm at the limit of its upward movement.
5. In combination with an elevated track-way, a body, a swinging bottom for said body, arms extending upwardly from the body at opposite ends thereof and terminating in inwardly directed extensions, parallel members connecting said extensions and spaced one from the other, a pair of bell levers pivotally connected at their heel portions between the members, said bell levers having downwardly depending arms and

inwardly directed arms, the inwardly directed arms being in overlying relation, locking levers coacting with the swinging bottom and mounted for rocking movement intermediate their lengths; reversely extending rods engaged with the depending arms of the bell levers and the upper end portions of the locking levers; a vertically movable arm having its lower end portion straddling the overlapping portions of the inwardly directed arms of the bell levers, a laterally directed arm carried by the last named arm and supported for pivotal move- ment between the members connecting the extensions of the upstanding arms carried by the body, means for constantly urging the upper end portion of the locking levers outwardly; and a member carried by the track for imparting downward movements to the arm coacting with the bell levers. In testimony whereof I hereunto affix my signature in the presence of two witnesses.
